DAMPENING MEANS FOR PRESSING MACHINES

Application filed February 15, 1929. Serial No. 340,252.

This invention relates to pressing machines as garment and laundry pressing machines, and has for its object a particularly simple and efficient means for evenly dampening a dry article or garment preliminary to pressing it without wetting or over dampening it.

The invention consists in the novel features and in the combinations and constructions hereinafter set forth and claimed.

In describing this invention, reference is had to the accompanying drawings in which like characters designate corresponding parts in all the views.

15 Figure 1 is a side elevation of one form of pressing machine embodying my invention.

Figure 2 is an enlarged fragmentary side elevation.

Figure 3 is a front elevation of parts seen 20 in Figure 2, and also a sectional view of the manual control means for operating the intermediate plate.

Figures 4 and 5 respectively are a fragmentary plan and edge views of the intermediate plate, the edge shown being one of the closed edges at the ends of the intermediate plate.

Figure 6 is a fragmentary detail view illustrating a section through the intermediate plate and the coupling between the intermediate plate and the conduit through which a cooling air current is conducted to said plate.

This pressing machine comprises upper 35 and lower cooperating pressing elements, one of which is movable toward and from the other, means for dampening a garment as by projecting hot steam through the lower pressing element into the garment, a chilling plate movable into and out of position over the article on the lower pressing element to lightly and evenly condense the moisture in the garment preliminary to pressing it, means for actuating the movable element to close and open the press, and means for cooling the chilling plate.

50 I have illustrated my invention as embodied in a conventional type of pressing machine in which the cooperating pressing elements comprise a stationary buck 1 and a head 2

movable toward and from the buck, the buck being mounted on a bracket or goose neck 3 which in turn is mounted on a suitable frame 4; and the head being carried by the forward end of a lever 5 pivoted at 6 between its ends 55 to the frame and connected at its rear end to a suitable actuating mechanism. This actuating mechanism may be of any suitable form, size and construction and preferably power actuated mechanism is used. That 60 here illustrated includes a cylinder 7 having a piston rod 8 pivoted at 9 to the forwardly extending arm 10 of an angle lever pivoted at 11 at its angle and having an upwardly extending arm 12 pivoted at 13 to the lower 65 end of the link 14 which is pivoted at 15 to the rear arm of the yoke lever 5. The parts 12 and 14 form a toggle. The piston in the cylinder 7 is single acting.

The flow of motive fluid to and from the 70 cylinder 7 is controlled in any suitable manner as by push buttons and a release lever similar to those to be presently described, in connection with the means for operating the intermediate chilling plate.

The press is locked in closed position by the pressure in the cylinder and is opened, when the pressure therein is released, by springs 16 and 17.

The actuating mechanism and the control 80 therefor form no part of this invention.

The lower pressing element or buck 1 is provided with means as a valve 18 for controlling the flow of steam through perforations in the lower pressing element or buck, 85 the padding thereon, and the garment or article overlying the padding this valve being operated by a rod 20 connected to any suitable operating member as a pedal not shown.

90 The means for steaming the garment through the lower buck is well known and the construction thereof, per se, forms no part of this invention. The steaming operation insofar as this invention is concerned is 95 important only in connection with the chilling plate to be presently described.

The head 2 is also heated and is usually formed hollow in the ordinary manner to receive steam from any suitable source.

21 designates a chilling plate movable into and out of position overlying the work on the buck 1. This plate 21 is substantially coextensive with the buck or of sufficient extent to cover the article being operated upon and is supported by a movable carrier.

The carrier here illustrated consists of a pair of front and rear diverging rods 22, 23 movable across each end of the buck. The plate 21 is secured to the upper ends of rods 22 and 23 at 22^a, 23^a. The rod 23 slides in a bearing sleeve 23^b. This bearing sleeve 23^b is pivotally mounted on a pin 23^c projecting from the frame of the pressing machine. The lower ends of each pair of rods 22, 23 are secured to a shaft or stud 24 which moves vertically along a stationary guide 25 secured to the frame, the shaft 24 being also a rock shaft so that the carrier and the plate 21 have a fore and aft movement as well as an up and down movement. It will be understood that there are a pair of rods 23, 22, shaft 24 and guide 25 at each end of the buck.

25 The plate 21 is of metal and is formed hollow for receiving a cooling medium as air, and is preferably composed of top and bottom sheets 26, 27, the sheets being spaced apart to form a passage for the cooling medium between them. The sheets are spaced 30 apart by suitable spacers here shown as bosses or integral projections 28 projected from the top sheet 26, and secured at the apexes to the inner face of the bottom sheet 27, as by welding. The side margins of the sheets overlap each other as at 29 and are secured together as by welding. The front and rear margins are open, at least throughout the greatest part of their length, in order to 35 provide an inlet and an outlet for the air, the inlet being located at the rear edge of the plate.

The cooling means is preferably arranged to blow air through the plate and cool the 40 same only when the plate is in its open position as indicated by the dotted lines, Figure 2. This blowing means is illustrated diagrammatically and comprises a blower 30 having an outlet pipe 31 terminating in an 45 exit slot at 32 with which the inlet edge of the plate 21 comes into register when the plate is in open or inoperative position, that is, its position indicated by dotted lines, Figure 2.

50 The plate 21 and the carrier therefor is preferably power operated and as here illustrated, the means for actuating the plate comprises a cylinder 33 having a piston movable therein, the rod 34 of which is connected 55 to one arm of a lever 36 mounted on a rock shaft 37, this rock shaft extending transversely of the frame and having rock arms 38 on opposite ends thereof which are connected by links 39 to the studs or shafts 24. The piston in the cylinder 33 is single acting, and

the movement of the piston under the air pressure is against the action of a returning spring 40 connected to the arm 36.

The flow of air to and from the cylinder 33 is controlled by any suitable manually, operator-operated valve means. The valve means here shown comprises a valve casing 41 connected at one end to a pipe 42 leading to a source of compressed air, a normally closed spring pressed intake valve 43 in the casing, a normally open exhaust valve 44, and a manually controlled device as a push button 45 for operating the valves. The valves 43 and 44 are connected by a stem 46 so that they act as a unit, and the casing is connected to the cylinder 33 by a pipe 47 connected to the casing between the valves.

The motion of the push button is transferred to the valves through levers 48 and 49, the latter acting on the stem 50 of the exhaust valve. Obviously, depression of the push button 45 will close the exhaust valve 44 and open the intake valve 43 permitting air to flow to the cylinder 33 and actuate the piston therein, and hence through the levers 36, 38 and links 39 swing the carrier arms 22, 23 above the axis of the studs or shaft 24 and at the same time, move the shaft 24 vertically in the guides 25 thus in effect first swinging the plate 21 from its open dotted line position, Figure 2, over the buck and then down on the buck. Although this movement is the resultant of two components, and the latter part of the movement downwardly takes place while the links 39 are swinging in the part of their arcs of movement A, by far the predominating part of this last part of the resultant movement is downward:

55 The valves 43, 44 are held in their operated position by suitable means as a diaphragm 51 in a diaphragm chamber 52, the diaphragm acting on a sliding stem 53 which acts on one arm of the lever 49. The pressure side of the diaphragm chamber 52 is connected to the interior of the valve casing 41 by a passage 54. As soon as the button 45 is depressed to close the exhaust valve 44, and open the intake 43, the air pressure will pass into the diaphragm chamber and act on the lever 49 to hold the valves in their operated position, when the plate 21 is in its operative position.

Similar push buttons control the flow of motive fluid to the main cylinder 7 and operate to bring the head 2 down on the plate 21, and press the garment.

When the pressure in the diaphragm chamber 52 is released, the valves 43, 44 are free to return to their normal position, and the air to exhaust from the cylinder 33 back through the pipe 47, valve casing 41 and the exhaust passage 44^a controlled by the exhaust valve 44. The air is exhausted from the diaphragm chamber by a normally closed ex-

haust valve 54 located in the valve casing 55 and connected by a pipe 56 to the pressure side of the diaphragm chamber 52; the exhaust valve 55 being spring pressed and opened against the action of the spring by a release lever 57 acting on the stem of the exhaust valve 55. The release of the air in the cylinder 7 is controlled by a similar release lever 57, but as the operation of the actuating mechanism for the head forms no part of this invention, further description of the control of the flow of air to and from the cylinder 7 is unnecessary.

In operation, the operator lays a perfectly dry garment on the buck 1, depresses the button 45 to bring the plate 21 into position overlying the garment on the buck, and then opens the valve 18 to permit hot steam to pass into the garment through the buck. When the steam comes into contact with the cold plate 21, it evenly and lightly condenses the moisture in the garment and dampens the dry garment. The operator then operates the release lever 57 permitting the chilling plate 21 to return to its open position under the reaction of the spring 40. Thereafter, the operator operates the machine to bring the hot head down onto the damp article to press and dry the same. When the plate 21 is returned to its open position, indicated by the dotted lines, Figure 2, the air inlet on the rear edge thereof comes into registration with the outlet 32 of the air blowing pipe so that a cooling air current passes through the plate and cools the same for the next operation.

This machine is particularly advantageous in pressing dry laundry or newly manufactured garments as shirts and the like, which are made from clean cloth and have not been laundered. In other words, it is particularly advantageous for garment manufacturers as well as for other users where the garment comes to the pressers perfectly dry.

What I claim is:

1. A pressing machine including upper and lower cooperating pressing elements one of which is movable toward and from the other, the lower element having means associated therewith for projecting steam through the article thereon, a chilling plate movable into and out of position overlying the article on the lower pressing element in position to condense the steam in the garment and hence dampen the garment, means for moving the chilling plate independently of the movable pressing element and for moving the movable pressing element independently of the chilling plate.

2. A pressing machine including upper and lower cooperating pressing elements one of which is movable toward and from the other, the lower element having means associated therewith for projecting steam through the article thereon and a chilling plate movable

into and out of position overlying the article on the lower pressing element in position to condense the steam in the garment and hence dampen the garment, means for moving the chilling plate independently of the movable pressing element and for moving the movable pressing element independently of the chilling plate, and means for cooling said plate.

3. A pressing machine including upper and lower cooperating pressing elements one of which is movable toward and from the other, the lower element having means associated therewith for projecting steam through the article thereon and a chilling plate movable into and out of position overlying the article on the lower pressing element in position to condense the steam in the garment and hence dampen the garment, the plate being formed hollow, means for passing a cooling medium through the plate, means for moving the chilling plate independently of the movable pressing element and for moving the movable pressing element independently of the chilling plate.

4. A pressing machine including upper and lower cooperating pressing elements one of which is movable toward and from the other, the lower element having means associated therewith for projecting steam through the article thereon and a chilling plate movable into and out of position overlying the article on the lower pressing element in position to condense the steam in the garment and hence dampen the garment, means for cooling the plate when the plate is out of operative position, means for moving the plate into and out of operative position independently of the movable pressing element, and means for moving the movable pressing element independently of the plate.

5. In a pressing machine, the combination of upper and lower cooperating pressing elements, one of which is movable toward and from the other, means for projecting steam into the article lying on the lower pressing element, a chilling plate movable into position over said article to condense the steam in the article, and means located adjacent one side of said chilling plate when the same is in open position for cooling the plate.

6. A pressing machine including cooperating buck and head, one of which is movable toward and from the other, an intermediate plate coextensive with the buck and movable independently of the head into and out of operative position with respect to the article on the buck, the buck having means for projecting steam into the article and against the plate and means for moving the movable pressing element independently of the plate.

7. A pressing machine including cooperating buck and head, one of which is movable toward and from the other, an intermediate metal plate coextensive with the buck and movable into and out of position overlying

- the article on the buck, a carrier for the plate, a pivotal mounting for the carrier including a guide in which the carrier is slideable, means operable at will to actuate the carrier on its pivotal mounting to carry the plate into and out of position overlying the buck and to slide said carrier in said guide to carry the plate toward and from the buck.
8. A pressing machine including cooperating buck and head, one of which is movable toward and from the other, an intermediate metal plate coextensive with the buck and movable into and out of position overlying the article on the buck, a carrier for the plate, a pivotal mounting for the carrier including a guide in which the carrier is slideable, and manually controlled power means operable at will to actuate the carrier on its pivotal mounting to bring the plate into and out of position overlying the buck and to slide said carrier in said guide to carry the plate toward and from the buck.
9. A pressing machine including cooperating upper and lower pressing elements, one of which is movable toward and from the other, the lower element having means for projecting a fluid through the article thereon, a plate substantially coextensive with the lower pressing element, a carrier for the plate, a pivotal mounting for the carrier about which the carrier is movable to bring the plate into and out of position overlying the article on the lower pressing element, means for actuating the movable pressing element, and additional means for actuating the carrier about its pivotal mounting to move the plate into and out of position overlying the lower pressing element.
10. A pressing machine including in combination cooperating pressing elements; a chilling plate formed of upper and lower spaced apart plate elements; a carrier for the plate operable to carry the plate into and out of position overlying one of the pressing elements; means for cooling the plate, said means including mechanism for forcing a cooling current between the upper and lower elements of the cooling plate, and a conduit from said mechanism located in position with respect to the pressing machine so that the end of the conduit is in position to direct the cooling currents between the plate elements of the chilling plate, when the same is in inoperative position.
11. A pressing machine including in combination, cooperating pressing elements; a hollow plate formed with inlet and outlet slots in the respective edges thereof; a carrier for said plate operable to carry the plate into and out of position overlying an article on one of the pressing elements; means for cooling the plate including a conduit; means for creating a cooling current through the conduit, an end portion of said conduit having an outlet of slot formation located in position with respect to the frame of the pressing machine so that it registers with the inlet slot of the hollow plate when said hollow plate is in inoperative position.
12. A pressing machine including in combination, cooperating pressing elements; a chilling plate formed of upper and lower spaced apart plate elements to form a hollow chamber closed at the ends but open along the front and rear edges; spacers between said plate elements; a carrier for the plate operable to carry the plate into and out of position overlying one of the pressing elements; means for cooling the plate, said means including mechanism for forcing a cooling current between the upper and lower elements of the cooling plate, and a conduit from said mechanism located in position with respect to the pressing machine so that the end of the conduit is in position to direct the cooling currents between the plate elements of the chilling plate, when the same is in inoperative position.
13. In a pressing machine in combination, cooperating pressing elements; a chilling plate movable into and out of operative position with respect to one of said pressing elements; actuating means for said chilling plate including a pivoted carrier; a motor to operate said pivoted carrier to move the chilling plate into position over the pressing element and lower said chilling plate into contact with the pressing element.
14. In a pressing machine in combination, cooperating pressing elements; a chilling plate; a pivotal mounting for the chilling plate about which the plate is movable into and out of position over one of said pressing elements; crank actuating means for moving said chilling plate about its pivotal mounting; mechanism for operating said crank means and for moving the plate into operative position.
- In testimony whereof, I have hereunto signed my name, at Syracuse, in the county of Onondaga, and in the State of New York, this 13th day of February, 1929.
- PHILIP N. BRAUN.
